UNITED STATES PATENT OFFICE.

HARRY H. ARMSTRONG, OF OAKMONT, CHARLES H. CURRY, OF PITTSBURG, AND FRED-
ERICK F. HARROLD, OF HOMESTEAD, PENNSYLVANIA, ASSIGNEES TO STANDARD
STEEL BOX COMPANY, OF PITTSBURG, PENNSYLVANIA, A CORPORATION OF WEST
VIRGINIA.

METAL BOX.

988,062.

Specification of Letters Patent. Patented Mar. 28, 1911.

Application filed May 15, 1909. Serial No. 496,816.

To all whom it may concern:

Be it known that we, HARRY H. ARMSTRONG, resident of Oakmont, CHARLES H. CURRY, resident of Pittsburg, and FRED-
ERICK F. HARROLD, a resident of Homestead, all of the county of Allegheny and State of Pennsylvania, have invented a new and useful Improvement in Metal Boxes; and we do hereby declare the following to be a full, clear, and exact description thereof.

Our invention relates to metal boxes for the transportation of beer, milk, or like bottles.

The object of the invention is to provide an open bottom metal box with compartments formed therein to receive the bottles, the parts being so combined as to give lightness with great rigidity and strength so as to withstand the severe usage to which such boxes are subjected in handling.

To these ends our invention comprises, the novel features hereinafter set forth and claimed.

In the drawings Figure 1 is a side elevation partly broken away of our improved box; Fig. 2 is an end view partly broken away; Fig. 3 is a section taken on the line 3—3, Fig. 1; Fig. 4 is a section on the line 4—4, Fig. 3; Fig. 5 is a section on the line 5—5 Fig. 2; Fig. 6 is a modified form of the manner of supporting the supporting bars; Fig. 7 is an enlarged section on the line 7—7 Fig. 8; Fig. 8 is a plan view of a portion of the box; Fig. 9 is a plan view of a modification; and Fig. 10 is a detail of the manner of securing the partitions.

In the drawing the numeral 2 designates the box which is formed of the sides and ends composed of metal of suitable gage, and ribbed as at 3 to stiffen the sides and ends and add to the rigidity of the box. Surrounding the box at the edges of the bottom thereof is the bar 4 which is rectangular in cross section and said bar is bent at the corners to form rounded corners. The metal, at or adjacent to the lower edges of the sides and ends is bent around the bar 4, the metal as indicated in Fig. 1 being bent outwardly, as at 5, to form the shoulder 6 and is then bent down around the bar and up on the inside thereof, as at 7.

Around the upper edge of the box is the angle 8 with which the metal at the upper portions of the sides and ends is adapted

to engage, said metal being bent over and around and under the angle, as indicated at 9. Resting on the inwardly projecting flange of the angle bar 8 at each corner of the box are the angular pieces of wire, or other suitable material 10 which are covered by the metal of the sides and ends of the box and are held securely in place thereby. These wires taper off at their ends, as at 11, and said wires form the stacking ridges so that when the boxes are placed one upon the other they can be supported in the manner indicated in Fig. 1.

The longitudinal supporting bars 12 are formed of metal bent to inclose the wire beading 13 at the bottom thereof and one side of said bar is extended beyond the other, as indicated at 14. The bars 12 are further provided at intervals with the openings 15. The bars 12 are supported at their ends on the bar 4 and the ends of said bars 12 are flattened out, as at 16, so as to rest evenly on the bar 4. The side portions of the bar 4 at their ends project through openings 17 in the end walls of the box and said projecting ends are then bent back, as indicated at 18, to secure the supporting bars 12 rigidly in position. The bottom cross-bars 19 extend through the openings 15 in the supporting bars 12 and said cross-bars are preferably T-shaped in form, being composed of the metal sheet bent in the T-form with an additional strengthening member 20 inclosing the cross-arm of the T, thereby giving greater strength and rigidity and making it dirt proof. The T-bar 19 is cut away at intervals to form the notches 21 and when the cross-bars 19 are brought into engagement with the supporting bars 12 said cross-bars are inserted in the openings 15, said openings being of sufficient height to receive the entire height of the T-bar. When the notches 21 come into coincidence with the beading 13 on the supporting bars 12 the T-bar is lowered so that the notches 21 may engage said beading and extend down on both sides thereof to partially inclose said beading, as indicated in Fig. 3, and the lower edges of said T-bars are flush or substantially so with the lower edges of said supporting bars. This makes the boxes ride easier in the traveling conveyers in the breweries with less bumping and jolting. In order to hold the cross-bars 19 down in

position within the openings 15 so that the notches will always engage the beading 13 of the supporting bars the extended portion 14 is provided on one of the sides of the 5 supporting bars 12 so that when the T-bar has been inserted through the openings in the supporting bars, as indicated, the extended portion 14 is bent down to engage or come close to the upper face of the T-bars 10 and so prevent their rising. In this manner the T-bars are locked securely in position against vertical movement and by having the notches 21 in said T-bars engaging the beading 13 of the supporting bars the 15 T-bars are also held against any longitudinal movement as well as vertical movement. The ends of the cross-bars 19 project through openings 22 in the side walls and the projecting metal is bent over, as at 23, 20 in order to secure the cross-bars to the side walls of the box.

The box is provided with compartments to receive the bottles and these compartments are formed by the partitions 24 and 25. The partitions 25 extend cross-wise of the box and are provided with slots 26. The metal at the upper and lower edges of the partitions 25 is bent around the wires 27 to form a beading at the upper and lower edges 30 of the partitions 25. The beading 27 at the lower edges of the partitions 25 has notches 27^a which engage notches 28 in the supporting bars 12 while the beading at the upper edge of the partitions 25 take into notches 35 29 in the partitions 24. In this manner the partitions 25 are held at their upper and lower edges to prevent lateral movement. The partitions 25 have their upper beading projecting through openings 30 in the side 40 walls of the box and the metal is then pressed to form a rivet head to secure the partitions 25 to the side walls. In assembling the partitions 24 and 25 the partitions 24 are inserted within the slots 26 of the 45 partitions 25 and the openings 31 in the end walls to receive the projecting upper beading 32 of the partitions 24 are made at such a height that when the partitions 24 have been inserted in the slots 26, said partitions 50 may be raised so as to have their notches engage the beading 27 at the upper edges of the partitions 25. When the partitions 24 have been raised to this position their upper beading 32 will be in alignment with the 55 openings 31 and can be then passed through said openings and the beading riveted to the ends of the box to secure the partitions 24 in place.

By the above construction it will be observed that the partitions when secured in place form an interlocking structure in which the cross partitions are held from any lateral movement by engaging the notches in the partitions 24 as well as by their engagement with the upper edges of the sup-

porting bars 12. The partitions 24 by this same construction are held as against any longitudinal movement, any tendency to lateral movement being cared for by their engagement with the slots in the partitions 25.

By the above construction all the parts of the box are so united and braced as to provide a structure in which none of the parts can work loose and cause rattling, while at the same time the rigidity obtained is such as will enable the box to withstand the rough treatment to which such boxes are subjected in transportation and handling.

In Fig. 6 we have illustrated a modified 80 form of the invention in which the metal of the sides and ends at the lower edges thereof in taking around the lower bar 4 is bent to form the recessed portion 35 and the ends of the supporting bars 12 are extended so as 85 to enter said recess and give a longer support for the supporting bars 12 at the ends thereof.

In Fig. 9 we have illustrated a modified 90 form of our invention in which the stacking ridges are formed at points intermediate the corners of the box.

What we claim is:

1. A metal box having an open bottom comprising supporting bars having beadings 95 at the lower edges thereof and having enlarged openings therein, bottom bars passing through said openings and having notches engaging said beadings, and means for preventing the upward movement of said bottom bars.

2. A metal box having an open bottom comprising supporting bars having beadings at the lower edges thereof and having openings formed therein, bottom bars entering 105 said openings having notches engaging said beadings, and portions on said supporting bars engaging the upper faces of said bottom bars.

3. A metal box having an open bottom 110 comprising supporting bars having beadings at the lower edges thereof and having openings formed therein, bottom bars entering said openings having notches engaging said beadings, and portions on said supporting bars bent to engage the upper faces of said bottom bars.

4. A metal box having an open bottom comprising supporting bars, beadings at the lower edges thereof and having enlarged 120 openings therein, T-shaped bottom bars passing through said openings having notches formed therein adapted to engage said beadings, and portions of said supporting bars adapted to hold said T-bars in engagement with said beadings.

5. A metal box, an inwardly extending bar around the upper edge of said box, the metal of the sides and ends passing over said bar and stacking ridges formed of metal 130

pieces resting on said bar intermediate the edges thereof and held in place by the overlapping metal of the sides and ends.

6. In a metal box, a bar at the upper edge thereof, the metal of the sides and ends engaging said bar, and stacking ridges formed of metal pieces resting on said bar intermediate the edges thereof and engaged by the overlapping metal of the sides and ends.
- 10 7. In a metal box, a bar at the upper edge thereof, the metal of the sides and ends engaging said bar, and wire pieces bent to conform to the angles of the corner resting on

said bar intermediate the edges thereof and engaged by the over-lapping metal of the 15 sides and ends.

In testimony whereof, we the said HARRY H. ARMSTRONG, CHARLES H. CURRY and FREDERICK F. HARROLD have hereunto set our hands.

HARRY H. ARMSTRONG.

CHARLES H. CURRY.

FREDERICK F. HARROLD.
